CLAIM

The ornamental design of a lighting fixture, as shown and described.

DESCRIPTION

FIG. 1 is an underside isometric view of a lighting fixture incorporating our new design, wherein the break lines indicate indeterminate length and the phantom lines form no part of the claimed design;

FIG. 2 is a top side isometric view of the lighting fixture of FIG. 1, wherein the break lines indicate indeterminate length and the phantom lines form no part of the claimed design;

FIG. 3 is a side elevation view thereof;

FIG. 4 is a front end elevation view thereof;

FIG. 5 is a bottom plan view thereof;

FIG. 6 is a top plan view thereof;

FIG. 7 is an underside isometric view of another embodiment of a lighting fixture incorporating our new design, wherein the break lines indicate indeterminate length and the phantom lines form no part of the claimed design;

FIG. 8 is a top side isometric view thereof, wherein the break lines indicate indeterminate length and the phantom lines form no part of the claimed design;

FIG. 9 is a side elevation view thereof;

FIG. 10 is a front elevation view thereof, wherein the break lines indicate indeterminate length and the phantom lines form no part of the claimed design;

FIG. 11 is a bottom plan view thereof, wherein the break lines indicate indeterminate length and the phantom lines form no part of the claimed design;

FIG. 12 is a top plan view thereof, wherein the break lines indicate indeterminate length and the phantom lines form no part of the claimed design;

FIG. 13 is an underside isometric view of another embodiment of a lighting fixture incorporating our new design, wherein the break lines indicate indeterminate length and the phantom lines form no part of the claimed design;

FIG. 14 is a top side isometric view thereof, wherein the break lines indicate indeterminate length and the phantom lines form no part of the claimed design;

FIG. 15 is a side elevation view thereof;

FIG. 16 is a front elevation view thereof, wherein the break lines indicate indeterminate length and the phantom lines form no part of the claimed design;

FIG. 17 is a bottom plan view thereof, wherein the break lines indicate indeterminate length and the phantom lines form no part of the claimed design;

FIG. 18 is a top plan view thereof, wherein the break lines indicate indeterminate length and the phantom lines form no part of the claimed design;

FIG. 19 is an underside isometric view of another embodiment of a lighting fixture incorporating our new design, wherein the break lines indicate indeterminate length and the phantom lines form no part of the claimed design;

FIG. 20 is a top side isometric view thereof, wherein the break lines indicate indeterminate length and the phantom lines form no part of the claimed design;

FIG. 21 is a side elevation view thereof;

FIG. 22 is a front elevation view thereof, wherein the break lines indicate indeterminate length and the phantom lines form no part of the claimed design;

FIG. 23 is a bottom plan view thereof, wherein the break lines indicate indeterminate length and the phantom lines form no part of the claimed design; and,

FIG. 24 is a top plan view thereof, wherein the break lines indicate indeterminate length and the phantom lines form no part of the claimed design.
